145,371

DESIGN FOR A SWEATER

Berté A. Wiechmann, Portland, Oreg., assignor to Jantzen Knitting Mills, a corporation of Oregon

Application March 16, 1946, Serial No. 127,594

Term of patent 3½ years

(Cl. D3—4)

To all whom it may concern:

Be it known that I, Berté A. Wiechmann, a citizen of the United States, residing at Portland, in the county of Multnomah, State of Oregon, have invented a new, original, and ornamental Design for a Sweater, of which the following is a specification, reference being had to the accompanying drawing, forming a part thereof.

In the drawing, the single figure is a view of the front side of the sweater showing my new design, the design on the rear side of the sweater being the same as on the front.

I claim:

The ornamental design for a sweater, substantially as shown and described.

BERTÉ A. WIECHMANN.
